DESIGN FOR A DRESS

Doris Mandelker, New York, N. Y.

Application July 29, 1941, Serial No. 102,526

Term of patent 3½ years

To all whom it may concern:

Be it known that I, Doris Mandelker, a citizen of the United States of America, residing in New York city, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the cuff portion illustrating the beaded embroidery in detail.

I claim:

The ornamental design for a dress, substantially as shown and described.

DORIS MANDELKER.
